AXMINSTER-TYPE CARPET

Henry A. Reinhardt, Greenwich, Conn., assignor to Bigelow-Sanford Carpet Company, Inc., Thompsonville, Conn., a corporation of Delaware

Filed Oct. 28, 1957, Ser. No. 692,814

9 Claims. (Cl. 139—401)

The present invention relates to pile fabric floor coverings and more particularly to an improved pile fabric floor covering which may be made on an Axminster-type loom.

The traditional Axminster carpet employs a pile tuft cut from a pile yarn which is looped about a holding weft shot to form a generally V-shaped tuft having two legs which extend upwardly from the backing, at each side of the holding weft shot. The tuft legs at the base of the tuft are engaged between adjacent weft shots, as the fabric is beaten-up in the weaving operation, so that the portion of the pile yarn looped about the holding weft is tightly compressed. As the tufts extend upwardly from the backing fabric they open up, or "blossom out," that is, the individual fibers composing the tuft spread apart, becoming more widely separated at progressively greater distances above the backing fabric. Thus each tuft leg assumes a triangular or upwardly-flaring shape, as seen in cross-section taken warpwise of the fabric. The breadth in the warpwise direction of a whole tuft comprising two legs would, in the absence of restraint by the tufts of adjoining rows, be greater than the distance between adjoining tuft rows. The result is that one leg of a tuft in one row leans against the adjacent leg of the tuft in the adjoining row. As seen in warpwise cross-section, the adjacent tufts of two adjoining rows assume the shape of a W, wherein the lower points of the W constitute the bases of the tufts, the legs of each tuft being spread apart and the top of the leg of one tuft being pressed against the top of the leg of the adjacent tuft more closely than it is pressed against its companion leg of the same tuft. This effect is illustrated, for example, by the fabric shown in Fig. 1 of the Phoenix Patent No. 1,849,550. This effect results in an uneven or non-uniform distribution of pile fiber at the pile face of the fabric, as, at the pile face, the adjacent legs of two adjoining rows are more tightly pressed together, with resultant intermingling of fibers, than are the two legs of any single row.

Since both legs of a given tuft must be of the same color and texture, and thus the pattern can only be determined by changes of color of an entire tuft, such intermingling of adjacent tuft leg fibers tends, where the adjacent tufts are of different pattern colors, to obscure the pattern outline, detracting from definiteness of pattern delineation.

An object of the invention is to provide a woven pile fabric floor covering, woven on an Axminster loom, which has a more even and uniform distribution of pile fiber in the exposed pile surface than has heretofore been possible of attainment in Axminster manufacture.

Another object is to provide an Axminster-type fabric construction which provides a sharper pattern delineation for a given pitch than has heretofore been attainable in Axminster carpets.

A further object of the invention is to provide an Axminster-type fabric which affords a large saving in

2

pile material for a given degree of coverage of the fabric backing.

Another object is to provide an Axminster-type fabric construction which is more luxurious than heretofore known in Axminster-type fabric, in that it has a greater pile height.

The invention will be more fully understood from the accompanying drawings, wherein:

Fig. 1 is a diagrammatic perspective view, partly broken away, of typical 3-weft-plane fabric embodying my invention;

Fig. 2 is a warpwise cross-section of a 2-weft-plane fabric;

Fig. 3 is a warpwise cross-section of a single-weft-plane fabric;

Fig. 4 is a side elevation, somewhat schematic, of a loom on which my method may be practiced for the manufacture of the fabric of my invention;

Figs. 5-9 inclusive are schematic transverse sections 20 of the loom at the weaving point illustrating respectively successive steps of the method; and

Fig. 10 is a diagrammatic warpwise sectional view of a fabric similar to that of Fig. 1 showing a modification.

In accordance with the invention I provide an Axminster type woven pile fabric wherein the pile tuft instead of being V-shaped and looped about a holding weft shot as in the traditional Axminster, consists of a single leg only, the leg extending above the upper face of the backing and being securely bound in the backing 30 by being passed between adjacent pairs of weft shots and turned at its lower end to underlie a weft shot. The wefts in my fabric, as in conventional Axminster fabric, are inserted in pairs by a needle and I employ the term "weft shot" herein to designate such a pair of simultaneously-35 inserted wefts which function in the fabric construction as a single weft unit.

In order that the disclosure and description hereinafter of my method of manufacture of my fabric may be clearly understood I will first briefly describe the Axminster-type loom on which the method is practiced. Referring to Fig. 4 of the drawing, the loom frame comprises a pair of side frame members 2 joined by cross-girths (not shown). The main shaft 4 extending between the side frames 2 carries a series of cams which operate 45 the various loom mechanisms in properly timed relationship. The binder warps 6 and stuffer warps 8 are supplied from a beam (not shown) from which they pass forwardly of the loom as shown to the weaving point or fell 40 of the carpet. From the fell the woven carpet 50 passes forwardly across the breast beam 10 to a suitable take-up roll (not shown). Suitable heddles (not shown) are provided to shed the various warps.

The pile yarns are supplied from a series of tube frames 14 carried on an overhead carrier chain 12. 55 Each tube frame 14 has a row of small metal tubes 16 projecting therefrom, from each of which tubes one of the warp yarns 18 protrudes. Each tube frame is taken in turn from the carrier 12 by a pair of clutch arms 20 and lowered to the weaving point. At the weaving point the tube frame is rocked counterclockwise about a horizontal axis by means of the rod 22, bell crank 24, rod 26, cam follower 28 and a cam 30 on main shaft 4. This rocking produces the so-called "wiping-in" action in which the tips of the tubes 16 are entered 60 between binder warps and then moved downwardly and forwardly to carry the pile yarn ends 18 below the binder and stuffer warps, whereupon the tube frame and tubes are lifted, at the end of the wiping-in action, to clear the tubes from the warps, leaving a short length 65 of pile yarn extending downwardly from the tube and between the binder warps and stuffer warps. This lift- 70

ing action of the tube frame is effected by the cam segment 32 of cam disc 34 carried by the main shaft 4.

The lay 36 which carries the reed 38 is operated by a cam on the main shaft 4 to swing to and from the fell 40 of the cloth to beat-up the wefts.

The wefts are inserted by a needle 42 adapted to be passed transversely through the shed between the reed in its backward position and the fell, laying two wefts at the same time so that the wefts of the completed fabric are disposed in pairs.

A comb 44 is mounted for a conventional put-out and put-up movement by which, in the case of the conventional Axminster fabric, it engages the pile yarn ends 18 depending below the warps, to turn them upwardly about the last-inserted holding weft shot to form the second pile tuft leg. While the comb 44 is dwelling in its up position and engaging the fell 40 of the carpet, the tube frame 14 is given an upward movement by the draw-off cam segment 50 on the cam disc 34 to draw additional pile yarn from the spools on the frame to provide the protruding ends 18 for the next row of tufts to be formed by that tube frame.

Thereafter, the pile yarn is severed at the desired height above the cloth backing by knives 46, 48. Finally, the tube frame is raised by the clutch arms 20 and re-attached to the carrier chain 12, which then advances to bring the next tube frame 14 into position to be engaged by the clutch arms as the cycle is repeated to form the next row of the next row of tufts.

Turning now to Figs. 5, 6, 7, 8 and 9, the details of my method of making the fabric of the invention will be described. In Fig. 5 the tube frame 14 has been lowered from the carrier chain 12 and the tubes 16 with the protruding yarn tufts 18 have been inserted between the warps at the beginning of the wiping-in action. The reed 38 at this time is in its rearward position. Previous to this stage the pair of upper wefts 60 had been inserted and beat-up and, thereafter, the pair of binding wefts 62 had been inserted and beat-up. As appears in Fig. 5, the upper weft pair 60 is disposed forwardly of the weft pair 62, that is, to the right in Fig. 5.

As the wiping-in action continues, the tubes 16 rotate counter-clockwise (by rod 22 and cam 30, Fig. 4) and then are lifted (cam 32, Fig. 4) into the position in which they appear in Fig. 6 with the pile yarn ends 18 extending between and slightly below the warps and lying against the weft pair 62. As the tuft is to have only one leg, the yarn end 18 need extend downwardly only sufficiently to provide the length of yarn which is to be bound into the backing to hold the tuft in place, in contrast to the usual Axminster procedure in which the yarn must extend enough lower, than in my method, to provide a second leg for the same tuft. The proper height or vertical position of the tube frame 14 at the end of the wiping-in action to provide sufficient tuft yarn to be bound into the fabric, but not sufficient to provide a second leg on the tuft, is accomplished by appropriate adjustment of the cam segment 32, having regard to the other adjustments of the loom, as will be readily understood by those skilled in the art.

At this point, as appears in Fig. 6, a pair of holding wefts 64 are inserted in the shed by the needle and then beat-up by a forward movement of the reed 38 into the position shown in Fig. 7. As the weft pair 64 is beaten into the fell it moves into a position above the pair of binding wefts 62, causing the lower end of the pile yarn to be bent as shown in Fig. 7 and disposed between the pair of holding wefts 64 and the pair of binding wefts 62. The pile yarn above is driven forwardly into engagement with the pair of upper wefts 60. The reed then moves backwardly into its dotted line position of Fig. 7.

In normal Axminster manufacture when the reed 38 is returned to its dotted position of Fig. 7 the comb 44 would be put out and put up to engage the extending

portion of the pile yarn and turn it upwardly about the holding weft 64 to form the second pile tuft leg. This action of the comb is not required in the present method as there is no second pile tuft leg, and the comb may be disabled or may be removed from the loom. However, the comb may be retained and there is no objection to allowing the comb to move in its normal manner. As appears in Fig. 8, the comb 44 has been put out and put up and lies against the fell 40 of the cloth. Necessarily, any extent of pile yarn rearwardly of the holding wefts 64 will be turned upwardly by the comb to extend toward the upper surface of the backing or slightly thereabove.

The tube frame 14 now receives its upward, draw-off movement, moving into the position shown in Fig. 8 to leave extending from the tubes 16 a length of yarn sufficient to provide the first tuft leg 66 of the tuft which has just been formed, and, in addition, to provide an end 18 to protrude from the tube for use in forming the next tuft to be formed by that tube. The comb as it lies against the fell of the cloth during this draw-off motion of the tube frame is useful in tending to prevent slippage of the pile yarn between the wefts 64 and 62 during draw-off.

The pile yarn is then cut, Fig. 9, by the cutters 46, 48, leaving the newly formed tuft with a single pile leg 66 of the desired height and leaving the yarn end 18 protruding from the tube 16.

Thereafter another pair of upper wefts 60 is inserted and the cycle repeated.

In its draw-off movement the tube 16 need not be raised as far above the line of action of blades 46, 48 as it must be raised in the conventional Axminster manufacture, as the amount of yarn which must be left protruding as an end 18 is only that required to form a single-legged tuft, as contrasted with a two-legged tuft. This departure from the conventional Axminster method is taken care of by appropriate adjustment of the cam segment 50, having regard to the other adjustments of the loom including the adjustment of the cam 32, as will be readily understood by those skilled in the art.

From time to time the binder warps 6 and the stuffer warps 8 are shedded by the heddles in the conventional manner, as will be well understood.

Although only a single tuft 66 has been referred to in the foregoing description, it will be understood that each tube frame 14 carries a row of tubes 16, perpendicular to the paper of the drawing and that accordingly a weft-wise row of tufts like tuft 66 is formed simultaneously therewith.

The result of this method of weaving is the fabric of my invention illustrated in Figs. 1, 2 and 3. Referring to Fig. 1, the fabric comprises (1) the backing structure made up of wefts, binder warps and two planes of stuffer warps, indicated generally at 68, and (2) the pile face composed of pile tufts indicated generally at 70. Each pile tuft consists of a single leg 66 extending uprightly above the upper wefts 60 and having its lower end 72 turned approximately at a right angle to lie between and be tightly engaged by the holding weft pair 64 and the binding weft pair 62 therebelow. The upper wefts 60, in pairs, are bound down against the stuffer warps 74 of the upper plane of stuffer warps by the binder warps 76 which pass above the wefts 60. When the wefts 60 have been inserted the shed is changed to bring the binder warp 76 down so that the next pair of wefts, which is the pair of binding wefts 62, is placed above the binder warp 76. The stuffer warps likewise are appropriately shedded so that the binding wefts 62 are below both planes of stuffer warps and the holding wefts 64 are between the planes of stuffer warps. When wefts 60, 62 and 64 have been placed the shed is again changed so that the next pair of upper wefts 60 is disposed above the upper plane of stuffer warps and below the binder warp 76.

In my fabric every pile tuft leg is structurally the same as every other pile tuft leg, and is related to its neighboring tufts in the same way as every other tuft leg is related to its corresponding tufts. The result is that in my fabric the pile fibers are uniformly and evenly distributed at the pile surface of the fabric. The pattern delineation at the border line between tufts of different colors is sharper and more distinct than in the conventional Axminster, as tuft legs of different colors are never pressed together more strongly, with intermingling of fibers, than are tuft legs of the same color, as occurs in conventional Axminster.

A further advantage of my method and product is that the pile height may be considerably higher than is possible with the ordinary Axminster method and product, other factors remaining the same. In the ordinary Axminster construction the height of the pile is limited by the length of pile yarn 18 which may be allowed to protrude from the tubes 16. If this protruding end 18 is too long, it is impossible to wipe-in the tubes and yarns, as the yarns hang up on the warps. For this reason, in Axminster weaving, the yarn ends 18 can not exceed a predetermined maximum length. With my method, this maximum length of yarn 18 will provide a pile tuft considerably higher than that possible with the conventional Axminster method, inasmuch as the length 18 in my method does not provide a tuft leg but only the length required to be bound-in between the wefts 64, 62. In contrast, in the conventional Axminster method this length 18 must provide the yarn for both the length which is bound in and one of the tuft legs.

By the employment of pile of increased height, the warpwise spacing between rows may be increased while obtaining the same degree of coverage of the backing with consequent saving of expensive pile yarn. Also, with increased pile height, the fabric may be designed with many "outs" or missing tufts without impairing the coverage of the backing. Such reduction in the number of tufts per square inch which my invention makes possible provides further possibility of savings in the expensive pile yarn.

My invention is not limited to the construction shown for purposes of illustration in Fig. 1. The invention may be applied to any kind of Axminster construction. It also may be applied in the form of 2-shot or 1-shot fabrics.

Referring to Fig. 2, a 2-shot fabric is illustrated wherein the wefts are arranged in two planes, one above and one below the stuffer warps 78. The pairs of upper or holding wefts 84, 86 are bound down against the stuffer warps and the pairs of lower or binding wefts 88, 90 are bound up against the stuffer warps by the pairs of binder warps 80, 82 which pass alternately above weft pairs in the upper plane and below weft pairs in the lower plane. The wiping-in action occurs following the insertion of a binding weft pair 88, 90 whereupon an upper or holding weft pair 84, 86 is inserted and when beaten-up bends the pile yarns to cause the lower ends to be turned at an inclination to lie between and be engaged by a binding weft pair 88, 90 and a holding weft pair 84, 86, leaving the greater part of the tuft 66 extending upwardly between adjacent pairs of holding wefts 84, 86 to provide a single tuft leg.

A 1-shot construction is illustrated in Fig. 3 wherein there are no stuffer warps and the wefts 92, 94 are in pairs lying in a single plane. One set of binder warps 96 passes over alternate pairs of weft shots and under the intermediate pairs of weft shots and the other set of binder warps 98 passes under said alternate weft shots and over said intermediate weft shots. The pile yarns are wiped-in as described above and wiping-in is followed by the insertion of a pair of wefts which are beaten-up to engage the pile yarn between that pair and the preceding weft pair so that the tuft has a single leg 66 extended upwardly between adjacent pairs of wefts. Since there is

5 a single plane only of wefts the lower ends 102 of the pile yarns are not turned by means of the insertion of a weft pair. When the fabric has been woven, it is back-coated with an adhesive composition 100, as by 10 coating with a doctor blade, so that the lower ends of the pile yarns which extend between the weft pairs are turned to lie against the back of the backing and securely united thereto by the adhesive. Each tuft comprises a single leg 66 extending uprightly between adjacent weft pairs and having its lower end turned at an inclination to lie beneath one of said adjacent weft pairs. As in 15 the other described embodiment of the invention, the pile fiber at the exposed pile face is uniformly distributed.

Other variations of the fabric of the invention, e.g., 15 those of Figs. 1 and 2, may be back-coated with an adhesive, if desired, or as required to give the degree of tuft bind desired, as is well understood in the art.

It will be appreciated that the lower ends of the pile tufts 66 need not be so short as to terminate immediately 20 after they have passed across the bottom of the holding weft pair but may be somewhat longer and may be turned upwardly around the holding weft pair, as is the traditional Axminster tuft, to extend toward the upper surface of the backing or to extend between the wefts 25 of the upper plane or to extend above the upper surface of the backing, as is illustrated by the tuft 66' of Fig. 10. Such constructions, while they consume more pile yarn than my presently preferred embodiment illustrated in the drawing, nevertheless provide the substantial benefits 30 of the invention.

Other and further embodiments of the invention and modifications of the particular fabric constructions which have been described in detail to illustrate the application 35 of my invention may be made by those skilled in the art without departing from the spirit and scope of the invention and the following claims are intended to embrace all such modifications and embodiments.

The method disclosed herein is claimed in my co-pending application, Serial No. 840,341, filed September 40 16, 1959, as a result of a requirement for restriction herein.

I claim:

1. A woven pile fabric floor covering comprising a series of wefts disposed in pairs, a series of binder warps interwoven with the wefts to extend between and alternately above and below pairs of wefts and hold the wefts in place to form a backing, and a pile face comprising equally-spaced rows of pile tufts bound in said backing, each tuft consisting of a single leg extending upwardly between adjacent pairs of wefts and having its lower end turned at an inclination to underlie one of said adjacent pairs of wefts.

2. A woven pile fabric floor covering comprising a series of wefts disposed in pairs and arranged in three planes, stuffer warps extending transversely of the wefts 55 between the upper and middle planes of wefts and between the middle and lower planes of wefts, binder warps interwoven with the wefts to extend alternately above weft pairs in the upper plane and below weft pairs in the lower plane to securely bind together said wefts and stuffer warps and hold them in place to form a backing, and a pile face comprising equally-spaced rows of pile tufts bound in said backing, each tuft consisting of a single leg 60 extending upwardly between adjacent pairs of wefts and having its lower end turned at an inclination to lie between and be bound in position by weft pairs in different planes.

3. A woven pile fabric floor covering comprising a series of wefts disposed in pairs and arranged in three planes, stuffer warps extending transversely of the wefts 70 between the upper and middle planes of wefts and between the middle and lower planes of wefts, binder warps interwoven with the wefts to extend alternately above weft pairs in the upper plane and below weft pairs in the lower plane to securely bind together said wefts and stuffer warps and hold them in place to form a backing, and a 75

pile face comprising equally-spaced rows of pile tufts bound in said backing, each tuft consisting of a single leg extending upwardly between adjacent pairs of wefts in said upper plane and having its lower end turned at an inclination to lie between and be bound in position by a pair of wefts in the middle plane and a pair of wefts in the lower plane.

4. A woven pile fabric floor covering comprising a series of wefts disposed in pairs and arranged in an upper plane and in a lower plane, stuffer warps extending transversely of the wefts between the planes of wefts, binder warps interwoven with the wefts to extend alternately above weft pairs in the upper plane and below weft pairs in the lower plane to securely bind together said wefts and stuffer warps and hold them in place to form a backing, and a pile face comprising equally-spaced rows of pile tufts bound in said backing, each tuft consisting of a single leg extending upwardly between adjacent pairs of wefts and having its lower end turned at an inclination to underlie one of said adjacent pairs of wefts.

5. A woven pile fabric floor covering comprising a series of wefts disposed in pairs and arranged in an upper plane and in a lower plane, stuffer warps extending transversely of the wefts between the planes of wefts, binder warps interwoven with the wefts to extend alternately above weft pairs in the upper plane and below weft pairs in the lower plane to securely bind together said wefts and stuffer warps and hold them in place to form a backing, and a pile face comprising equally-spaced rows of pile tufts bound in said backing, each tuft consisting of a single leg extending upwardly between adjacent pairs of wefts in said upper plane and having its lower end turned at an inclination to lie between and be bound in position by a pair of wefts in the lower plane and one of said adjacent pairs of wefts in the upper plane.

6. A woven pile fabric floor covering comprising a series of wefts disposed in pairs and arranged in a single plane, binder warps interwoven with the wefts to extend above alternate weft pairs and below the intermediate weft pairs, other binder warps interwoven with the wefts to extend below said alternate weft pairs and above said intermediate weft pairs to securely bind together said wefts and hold them in place to form a backing, and a pile face comprising equally-spaced rows of pile tufts bound in said backing, each tuft consisting of a single leg extending upwardly between adjacent pairs of wefts and having its lower end turned at an inclination to underlie one of said adjacent pairs of wefts.

7. A woven pile fabric floor covering comprising a series of wefts disposed in pairs and arranged in a single plane, binder warps interwoven with the wefts to extend above alternate weft pairs and below the intermediate weft pairs, binder warps interwoven with the wefts to extend below said alternate weft pairs and above said intermediate weft pairs to securely bind together said wefts and hold them in place to form a backing, a pile face comprising equally-spaced rows of pile tufts bound in said backing, each tuft consisting of a single leg extending upwardly between adjacent pairs of wefts and having its lower end turned at an inclination to underlie one of said adjacent pairs of wefts, and an adhesive coating on the under surface of said backing securely anchoring said lower ends to said backing.

8. A pile fabric floor covering of the Axminster type which comprises a series of wefts disposed in pairs interwoven with a series of binder warps so that the warps extend between and alternately above and below weft pairs to hold them in place to form a backing, and pile tufts interwoven with said weft pairs to form a pile face, each tuft consisting of a single leg extending upwardly between adjacent weft pairs and having its lower end turned at an inclination to underlie one of said adjacent weft pairs.

9. A woven pile fabric floor covering comprising a series of wefts disposed in pairs, a series of binder warps interwoven with the wefts to extend between and alternately above and below pairs of wefts and hold the wefts in place to form a backing, and a pile face comprising equally spaced rows of pile tufts bound in said backing, each tuft consisting of a single leg extending upwardly between adjacent pairs of wefts and having its lower end turned at an inclination to extend beneath one of said adjacent pairs of wefts and turn upwardly at the opposite side thereof and extend between that weft and the adjoining weft but not sufficiently above the backing of the floor covering to constitute a tuft leg.
